UNITED STATES PATENT OFFICE.

EUGENE W. KNOWLTON, OF BUFFALO, NEW YORK, ASSIGNOR TO JOHN E. SMITH'S SONS COMPANY, OF BUFFALO, NEW YORK, A CORPORATION OF NEW YORK.

BUTTER-BLOCKING MACHINE.

Application filed September 30, 1920. Serial No. 413,698.

To all whom it may concern:

Be it known that I, EUGENE W. KNOWLTON, a citizen of the United States, residing at Buffalo, in the county of Erie and State of New York, have invented new and useful Improvements in Butter-Blocking Machines, of which the following is a specification.

This invention relates to a butter blocking and dispensing machine which is more particularly intended for use in hotels, restaurants and the like.

One of the objects of this invention is to provide a machine of this character which is comparatively simple in construction, easy to manipulate, reliable in operation, and readily dismembered for cleaning purposes, as well as accessible for repairing or renewing parts.

Other objects are to provide improved means for changing or regulating the feed of the butter past the cutter to obtain butter cakes or blocks of various thicknesses, as desired, and to insure cutting the butter into blocks of uniform thickness for a given adjustment of the feed mechanism.

The invention further resides in certain novel features of construction and arrangement of parts hereinafter more fully described and claimed.

In the accompanying drawings: Figure 1 is a sectional side-elevation of a machine embodying my improvements. Figure 2 is a top plan view thereof. Figure 3 is a front view thereof, partly in section. Figure 4 is a horizontal section on line 4-4, Fig. 3, showing parts thereof broken away. Figure 5 is an enlarged fragmentary vertical section on line 5-5, Fig. 2. Figure 6 is a fragmentary horizontal section on line 6-6, Fig. 5. Figure 7 is a fragmentary vertical section of the cutter operating mechanism. Figures 8 and 9 are enlarged vertical sections on the correspondingly-numbered lines in Fig. 2. Figure 10 is an enlarged vertical transverse section on line 10-10, Fig. 2. Figure 11 is a fragmentary perspective view of the piston. Figure 12 is a fragmentary vertical transverse section thereof.

Similar characters of reference indicate corresponding parts throughout the several views.

In its general organization, this machine

comprises a casing having a rotatable table 55 therein provided with containers or receptacles for the butter which is to be cut into blocks or paddies, said table also being provided with ice containers or boxes arranged between the butter receptacles. By the rotation of said table, these butter containers are adapted to be successively brought into register with a feeding mechanism which forces a predetermined thickness of butter through the open lower end of the respective 60 container, after which a cutter mechanism 65 operated in conjunction with the feeding mechanism, severs the projected portion of the butter from that remaining in the container.

Referring now to the drawings, 20 represents the casing constructed of any suitable material, such as enameled metal, and supported on legs 21. The front portion of the top of said casing preferably consists of 70 a cover section 22 suitably fastened to the adjacent side walls of the casing, while the rear portion of the top consists of a vertically-swinging lid 23 hinged to the rear wall of the casing and having a handle or knob 75 24 for operating it.

Arranged horizontally in the bottom of the casing is a rotatable or turn-table 25 fixed to an upright shaft 26 journaled at its lower end in a step bearing 27 formed in 80 the bottom of the casing, while its upper end extends through a bearing or opening 28 in the cover section 22. Collars 29 and 30 pinned or otherwise secured to the shaft prevent vertical displacement thereof. The extreme outer end of the shaft is provided 85 with a handle 31 by which it is turned to rotate the table. Mounted on the latter are a plurality of butter containers 32, preferably 90 square in cross section, which may be integral therewith or separate and removable therefrom. In either case, they are open at 95 both ends to enable the same to be filled with butter at one end and discharged at the other. The discharge aperture 32a of each 100 container is of smaller dimensions than its body, so as to mold the butter into the desired size or cross section, preparatory to cutting it into blocks.

Ice receptacles or chambers 33 are arranged in the space between the butter containers to afford the necessary refrigeration to keep the butter fresh and hard. The ta-

ble 25 is adapted to be rotated to successively position the butter containers at a predetermined point where the butter feeding mechanism is located. To arrest the movement of the table at the desired point, a stop is provided which preferably comprises a spring pressed pin or catch 34 arranged to engage locking recesses or notches 35 arranged in the underside of the table 5 adjacent the edge thereof, such a notch being located centrally opposite each butter container. As shown in Fig. 5, this catch is disposed horizontally in the front wall of the casing and provided with a knob 36 for 10 withdrawing it to release the table. 15

The mechanism for ejecting or feeding the butter through the discharge end of each container, is preferably constructed as follows:

20 37 indicates a vertically swinging base plate which normally closes a filling opening 38 in the central front portion of the cover-section 22 of the casing and below which the butter containers are adapted to be 25 successively brought. This base plate is hinged at its rear end to a fixed support 39 by means of a pintle 40, said support being fastened to the rear portion of the cover section 22 and having an opening 41 therein 30 through which the shaft 26 passes. Carried by and guided in the base plate 37 is a square piston or plunger 42 for forcing the butter through the container. The piston is provided with a rod or stem 43 extending upwardly through an opening 44 in said plate, the upper end of said rod being provided with a removable knob 43^a. The piston-rod is provided on two sides thereof with ratchet teeth 45, 46, of different sizes, whereby a 40 greater or less stroke may be imparted to the piston for cutting butter blocks of different thicknesses. Fulcrumed on a standard or bracket 47 adjacent the rear end of the base plate 37 is a vertically swinging lever or arm 48 whose central portion is forked to permit the piston rod to pass freely therebetween. Pivotally mounted in the forked portion of this lever, in rear of the piston rod, is a vertically oscillating feed pawl 49 which is normally held in engagement with one of the rows of ratchet teeth 45 or 46 of the piston rod by a spring 50. A detent 51 is arranged below the feed pawl and slidably mounted on the base plate 37, being normally held in 50 engagement with the ratchet teeth of the piston rod by a spring 52. The feed pawl and the detent serve to guide the piston rod on the base plate 37 and tend to press the same against the front side 53 of the guide opening 44, thereby keeping the rod properly centered.

The front portion of the lever 48 terminates in a yoke 54 having an irregular opening or cam face 55 with which co-operate 65 means for actuating said lever to feed the

piston downward in the butter containers. The preferred means for effecting this result comprise a transverse rock shaft 56 journaled at its ends in standards 57 mounted on the front portion of the base plate 37. Fixed to this shaft on opposite sides of the yoke 54 are collars 58 between which are mounted upper and lower anti-friction rollers 59 which engage the cam face of said yoke and cause the lever 48 to swing up and down as the shaft is oscillated. An operating handle 60 for this purpose is mounted on one end of this shaft. As shown in Figs. 2 and 10, the forward movement of the rock shaft is limited by a spring pressed pin 61 carried by the inner end of the operating handle and adapted to engage a shoulder 62 on the face of the adjacent standard 57.

Means are provided for varying the extent of movement of the feed lever 48 through the yoke 54 whereby the stroke of the piston 42 is likewise varied and consequently the thickness of the butter block to be severed. These devices are preferably constructed as follows:

Mounted on the shaft 56 between the right hand collar 58 and the adjacent standard 57 are two disks or controlling plates 63, 64 arranged side by side and capable of oscillating independently of each other and of said shaft. A coupling pin 65, carried by the said collar 58 is adapted to engage registering segmental slots 66, 67 in the plates 63, 64, respectively, said slots being of equal length. As shown in Figs. 8, 9 and 10, one of these plates, preferably the inner plate 63, is provided in its outer portion with an opening 68, the inner edge of which is provided with radial notches 69, 70, while the other plate 64 is provided in its outer portion with a single radial notch or keyway 71. Yieldingly carried by the outer plate 64 is a coupling key or dog 72 which is arranged in the notch 71 of the outer plate and adapted to engage one or the other of the notches in the inner plate 63. This key is preferably carried by a spring 73 secured to the plate 64 by a screw 74 and normally tending to hold said key in its inner position against the bottoms of the notches. A suitable head or finger piece 75 is arranged at one end of the key for disengaging it from one or the other of the notches 69. Extending inwardly from the right hand standard 57 is a stop pin 76 which engages a segmental slot 77 in the outer plate 64 and limits the extent of movement in both directions of said plate and its companion plate 63, which is adjustably connected therewith by the key 72 and notches 69, 70.

In the normal position of the parts shown in the drawings, reference being had more particularly to Figs. 8, 9 and 10, the key 72 is in engagement with the rear notch 69, and the segmental slots 66, 67 of the plates are

lapped or out of complete register with each other, shortening the arc of travel of the coupling pin 65 and effecting a comparatively short rearward stroke of the operating handle and consequently a short upward stroke of the lever 48 which elevates the feed pawl 49 one tooth on the piston rod 45. This results in a correspondingly short downward stroke of the piston when the operating handle is moved forward and the cutting of a relatively thin block of butter by the cutter mechanism hereinafter described. It will be understood that during the initial rearward movement of the operating handle, the coupling pin 65 travels idly in the slots of the plates until it engages the opposing end of the slot 66 of the inner plate 63, which causes both controlling plates to turn with the operating shaft 56 until arrested by the end of the slot 77 of the plate 64 engaging the fixed stop pin 76. The lever 48, on the other hand, is moved upward from the beginning of the operative stroke, inasmuch as the rollers 59 engage 25 the cam face of the yoke 54 at all times. When it is desired to cut thicker blocks of butter, the effective stroke of the piston must obviously be increased, and this is accomplished by withdrawing the coupling key 72 from the notch 69, turning the plate 63 rearwardly by means of its finger piece 63^a, and setting the key in the notch 70, thus bringing the segmental slots 66, 67 into complete register. The initial upward stroke 35 of the operating handle is now increased and the feed pawl raised two teeth, resulting in a longer stroke of the piston and a correspondingly thicker block of butter.

The cutter mechanism for intermittently severing the projected bar of butter co-40 operates with the ejecting mechanism, and is preferably constructed as follows:

78 indicates a cutter or knife of any suitable construction arranged to travel in a horizontal plane across the discharge end 45 of the particular butter container under the piston feeding mechanism. This cutter is mounted on a frame 79 of heavy wire or other suitable material having a downwardly bent shank 80 which extends through an outlet opening 81 in the bottom of the casing. This shank terminates in a laterally offset portion 82 which is fastened to an arm 83 secured to the lower end of a short 50 upright rock shaft 84 suitably supported in the bottom of said casing. The upper end of this rock shaft, which extends into the casing, is provided with an arm 85 having a spherical knuckle 86 at its outer end which 55 engages a socket 87 in a horizontally disposed link 88. The latter is connected with one arm of a vertically movable bell crank lever 89, while the other arm thereof is connected by links 90 with the lower end of a 60 vertically movable plunger 91 guided in a tube 92 fastened to the inner side of the adjacent front wall of the casing. A spring 93 surrounding the lower end of this plunger and bearing at one end against the lower end of the guide tube and at its other end 70 against a shoulder 94 of said plunger, tends constantly to force the latter upwardly, thereby moving the cutter to the position shown by dotted lines in Fig. 4. Pivoted to the outer controlling plate 64 is a depending push rod 95 which passes through a guide opening 96 in the hinged base plate 37 and engages the head 97 of the plunger 91. In the normal depressed position of the operating handle 60, the rod 95 together 75 with the resistance offered by the associated parts, holds the plunger down against the tension of the spring 93, in which position the cutter assumes the position shown by full lines in Fig. 4. The shank 80 of the cutter frame is arranged to engage the adjacent edges of the opening 81 to limit the movement of the cutter in both directions. A stop flange or collar 98 at the lower end 80 of the plunger limits the upward movement thereof.

The piston 42 is preferably constructed in such a manner that in withdrawing it from the butter container the resulting vacuum is broken to prevent the butter still remaining in the reduced discharge end thereof from being sucked or drawn up with the piston. In its preferred form, the piston is composed of two vertically-movable leaves 99 hinged at 100 to a head or horizontal plate 101 secured to a collar 102 fastened to the lower end of the piston rod 43. These leaves are provided on their undersides with pads 103 of rubber or similar resilient material, and the ends of the head 101 are provided with similar face pads 104, whereby a tight joint is produced between the piston and the butter container. For this purpose these pads project slightly beyond the marginal edges of the leaves and the head. The 105 inner edges of the leaves are hinged to opposite sides of said head and when the piston is lowered upon the mass of butter in the container, the leaves unfold in line with each other, as shown in Figs. 5 and 12, in 110 which position they abut against the bottom of the collar 102, limiting their upward movement beyond that point and forming a practically square rigid piston. When the piston is withdrawn from the container, its 115 hinged leaves fold downwardly by gravity and by their frictional engagement with the wall of the container. Each leaf is provided with a suitable stop, preferably a hooked stop-arm 105 secured thereto and 120 adapted to engage the opposite side of the piston rod to prevent the total collapse of the piston, as shown in Fig. 11.

In loading the machine with butter, it is 125 only necessary to open the hinged lid 23 of 130

the casing and successively fill the containers by turning the table 25. The hinged base plate 37 on which the piston feed and cutter actuating mechanism are mounted, may be 5 raised and swung backwardly after withdrawing the piston clear of the container and thereby enable the containers to be filled through the opening 38, if desired. This is especially advantageous when the machine is 10 placed with its back against a wall, where it is inconvenient to fill the containers from the rear of the machine. By removing the hinged pintle 40 from its mounting, it is possible to completely remove the base plate 15 37 and associated parts from the machine, facilitating cleaning of the parts as well as ready access for repairs etc. A clamping or cam-lever 106 pivoted on the front portion of this base plate is adapted to interlock 20 with the head or lip 107 of a post 107^a fastened to the adjacent portion of the casing, for reliably holding said plate down in its normal position. The post extends through an opening 108 in the base plate.

25 The locking catch 34 of the turn table 25, also serves as a support for the front part thereof, thus relieving the table from the downward strains incidental to forcing the butter through the containers. By this arrangement, breakage of the table is avoided and it is also prevented from rotating unevenly and wearing untrue.

The operation of the machine is as follows:

30 35 Assume the parts to be in the position shown by full lines in the drawings, in which the operating handle 60 is in a substantially horizontal position, the piston having just forced a square bar of the butter through the discharge end of the container and the cutter having severed a block and occupying its forward position underneath the container. To cut another block, the operator turns the operating handle rearwardly to a 40 45 substantially vertical position, as shown by dotted lines in Fig. 5, the initial movement thereof causing the coupling pin 65 to move idly in the segmental slots of the controlling plates 63, 64, which are simultaneously 50 55 turned rearwardly about said shaft by the upward thrust of the spring-pressed plunger 91 through the medium of the push rod 95. As the plunger rises in its guide tube, the cutter is swung rearwardly until the stop 60 65 collar 98 of the plunger engages the lower end of the guide tube, when the cutter assumes the dotted line position shown in Fig. 4. During the final rearward movement of the operating handle, the coupling pin 65 70 encounters the opposing end of the slot 77 of the inner plate 63 and causes both plates to turn with the operating shaft 56 until further movement of the latter is prevented by the end of the slot 77 of the plate 64 engaging the stop pin 76. As previously de-

scribed, the lever 48, through the medium of the yoke 54 and rollers 59 is swung upward during the full rearward stroke of the operating handle, thereby raising the feed pawl one tooth on the ratchet of the piston rod preparatory to its effective downward stroke. After thus moving the operating handle rearwardly, the operator swings it forwardly to its initial position, the first part of this movement forcing the piston 70 downward in the container in an obvious manner and projecting a portion of butter through the discharge end thereof. During the final forward movement of this handle, the coupling pin 65 engages the end of the slot 67 of the outer controlling plate 64, turning the latter forwardly and lowering the rod 95 to depress the plunger 91 which causes the cutter to swing forwardly and sever the projected portion of butter in the 75 80 85 form of a block.

The parts are so constructed and timed that the piston and the cutter operate alternately, the piston being at rest during the cutting stroke of the knife so as to cut neat blocks of uniform thickness for all adjustments of the piston feeding mechanism. For this purpose the cam opening in the yoke 54 is so constructed that after the piston has been forced downwardly a step the 90 95 rollers are ineffective during the final forward movement of the operating handle, thereby retaining the lever 48 in a neutral or stationary position during the time the cutter is operating.

Should it be desired to cut blocks of a different thickness, the piston is removed from the container and given a quarter turn to bring the other row of ratchet teeth into operative position with reference to the feed pawl 49. As previously described, the stroke of the operating handle may also be shortened or lengthened to vary the stroke of the piston and hence the thickness of the butter-blocks. The mechanism shown in the drawings affords four adjustments for this purpose, two being obtained by the coarse and fine ratchet teeth 45, 46 of the piston rod and the other two by the adjustment of the controlling plates 63, 64.

While my improvements are herein shown and described in connection with a butter blocking machine, they are obviously applicable to machines for blocking or serving other foods or articles.

I claim as my invention:

1. A machine of the character described, comprising a casing, a table rotatably mounted therein and having radial notches adjacent to the periphery thereof, butter containers arranged on said table and open at either end, an ejecting device adapted to co-operate with each container for intermittently discharging butter therefrom, and a retractible stop arranged radially of said 125 130

table and adapted to engage said notches to properly position each container in alignment with said ejecting device.

2. A machine of the character described comprising a casing, a table rotatably mounted therein, butter containers arranged in spaced relation on said table and open at either end, means for ejecting butter from each container, and receptacles adapted to contain a refrigerating medium and arranged in the spaces between said containers.

3. A machine of the character described, comprising a casing having a fixed cover portion provided with an opening and a movable cover portion, a table rotatably mounted in said casing, butter containers arranged on said table and adapted to register with the opening in said fixed cover portion, a plate movably mounted on the latter and normally closing said opening, and means carried by said plate for ejecting the contents of said containers.

4. A machine of the character described comprising a casing having an opening in its top, a butter container open at both ends arranged in said casing in alignment with said opening, a plate hinged to said casing and normally closing the opening therein, a piston for said container having a rod provided with ratchet teeth, a lever fulcrumed on said plate and provided with a yoke, a feed pawl on said lever, and means on said plate engaging said yoke for actuating said lever.

5. A machine of the character described comprising a casing, a butter container arranged in said casing and having a discharge opening, an ejecting device for expelling butter through said opening, means for actuating said ejecting device, a cutter movable transversely of the discharge opening, a rock shaft having rock arms one of which carries the cutter, a vertically-movable plunger operated by said actuating means, a vertically oscillating bell crank lever, a link connecting one arm of said lever with said plunger, and a horizontally disposed link connecting the other arm of said lever with the other of said rock arms.

6. A machine of the character described comprising a casing, a butter container arranged in said casing and having a discharge opening, an ejecting device in said container, an oscillatory lever fulcrumed on said casing and operatively connected to said ejecting device, means for actuating said lever, a cutter movable transversely of said discharge opening and having a rock arm, a vertically movable plunger operatively connected to said rock arm, and means controlled by said lever-actuating means for operating said plunger.

7. A machine of the character described, comprising a casing, a butter container ar-

ranged in said casing and having a discharge opening, an ejecting device in said container, a rock shaft journaled on said casing, means carried by said shaft for actuating said ejecting device, a transversely movable cutter arranged below the discharge opening of said container, a vertically-movable member for operating said cutter, and a push rod operated by said rock shaft for actuating said vertically-movable member.

8. A machine of the character described, comprising a casing, a butter container arranged in said casing and having a discharge opening, an ejecting device in said container, a rock shaft journaled on said casing and carrying a coupling-pin, a plate mounted on said shaft and having a segmental slot which engages said pin, a cutter movable across the discharge end of said container, a vertically-movable member for operating said cutter, and a push rod connected to said plate for actuating said vertically-movable member, and means carried by said shaft for actuating said ejecting device.

9. A machine of the character described comprising a container for butter, means for expelling the butter from said container, an oscillatory lever movable in the plane of movement of said expelling means for actuating the latter, and means for regulating the extent of movement of said lever.

10. A machine of the character described comprising a container for butter, means for expelling the butter from said container, an oscillatory lever for actuating said expelling means, a yoke carried by said lever, means engaging said yoke for actuating said lever, and means for regulating the extent of movement of said yoke-engaging means.

11. In a machine of the character described comprising a container for butter, means for expelling the butter from said container, an oscillatory lever for actuating said expelling means, a yoke carried by said lever, a rock shaft arranged at right angles to the plane of movement of said oscillatory lever, means secured to said shaft and engaging said yoke for actuating said lever, a member loosely arranged on said shaft and operatively connected to said yoke-engaging means, and means for limiting the extent of movement of said member to control the throw of said oscillatory lever.

12. In a machine of the character described comprising a container for butter, means for expelling the butter from said container, an oscillatory lever for controlling said expelling means, a yoke carried by said lever, a rock shaft arranged at right angles to the plane of movement of said oscillatory lever, bearings for said shaft, an actuating-member for said lever secured to said shaft and engaging said yoke, a mem-

ber loosely arranged on said shaft and having segmental slots, a coupling pin carried by said actuating member and engaging one of said slots, and a stop pin carried by the adjacent shaft-bearing and engaging the other of said slots.

13. A machine of the character described comprising a container for butter, means for expelling the butter from said container, means for actuating said expelling means, means for adjustably regulating the extent of movement of said actuating means, including a pair of rotatable plates having alined segmental slots, a coupling device forming part of said actuating means and engaging said slots, means for adjustably connecting said plates together to vary the effective working length of said slots, and means for limiting the extent of movement of said plates.

14. A machine of the character described comprising a container for butter, means for expelling the butter from said container, means for actuating said expelling means, means for adjustably regulating the extent of movement of said actuating means, including a pair of rotatable plates having alined segmental slots, a coupling device forming part of said actuating means and engaging said slots, one of said plates having a plurality of locking notches and the other a similar notch co-operating with either of the first-named notches, a locking member adapted to engage the notches of said plates to cause the latter to turn together, and means for limiting the extent of rotation of said plates.

15. A machine of the character described comprising a container for butter, a piston for said container, a rod for said piston

having ratchet teeth thereon, an oscillatory lever terminating at its free end in a yoke, a pawl carried by said lever and co-operating with said teeth to advance said piston, a transverse rock shaft, a handle for actuating said shaft, an actuating member for said lever secured to said shaft and engaging said yoke, a pair of members rotatably arranged on said shaft and controlling the extent of movement of said lever, said members being provided with alined segmental slots, a coupling pin carried by said actuating member and engaging said slots, means for adjustably connecting said plates to vary the effective working length of said slots, and a stop member on one of said plates for limiting the extent of movement thereof in either direction.

16. A machine of the character described comprising a casing having alined openings in its top and bottom, a butter container arranged in said casing and adapted to be positioned between and in line with said openings, a cover plate arranged over said top opening ad movable relatively thereto, means carried by said plate for discharging the butter from said container, and means arranged in said casing and operating between the container and said casing bottom for severing the discharged portion of the butter.

17. An ejector for butter containers comprising a rod, collapsible piston leaves mounted on said rod and hinged on an axis at right angles thereto, and stop-arms secured to said leaves and arranged to engage said rod for limiting the collapsing movement of the leaves.

EUGENE W. KNOWLTON.
